UNITED STATES PATENT OFFICE.

WILLIAM MOLT, OF SPALDING, NEBRASKA.

STAMP-CANCELING DEVICE.

1,061,862.

Specification of Letters Patent.

Patented May 13, 1913.

Application filed January 13, 1912. Serial No. 671,020.

To all whom it may concern:

Be it known that I, WILLIAM MOLT, a citizen of the United States, residing at Spalding, in the county of Greeley and 5 State of Nebraska, have invented new and useful Improvements in Stamp-Canceling Devices, of which the following is a specification.

This invention relates to hand stamp canceling devices, and one of its objects is to provide a device of this character having a flexible yielding connection between the die and handle, whereby the die will be squarely impressed regardless of the angle at which 10 the handle is held.

A further object of the invention is to provide a hand stamp in which the die is normally held at a working angle to the handle, and in which the backing spring is 20 maintained in proper relative position to exert pressure on the die.

A still further object of the invention is to provide a hand stamp having a die of simplified construction and universally 25 mounted in a novel manner to facilitate its application to the supporting shank.

The invention consists of the features of construction, combination and arrangement of parts, hereinafter fully described and 30 claimed, reference being had to the accompanying drawing, in which:—

Figure 1 is a side elevation of a stamp canceling device embodying my invention. Fig. 2 is a vertical longitudinal section 35 thereof. Fig. 3 is a vertical transverse section through the shank looking toward the die.

Referring to the drawing, 1 designates a handle of suitable construction, having a 40 threaded socket 2 to receive the threaded end 3 of a shank 4, said socket being arranged to dispose the shank at an obtuse angle to the handle, as shown.

The outer end of the shank is reduced to 45 form a neck portion 5 terminating in a spherical head or ball 6 which universally supports the die 7, which may be of any preferred construction. The back of the die is provided with a socket 9 receiving 50 the ball or head 6, and universally mounting the die upon the shank 4. The socket opens through the upper surface of the boss, as at 10, which opening is of proper form for the free movement of the neck 5.

As shown, the socket lug is provided with 55 equidistant notches 11 forming intervening fingers 12. These fingers, which are normally spread open, are bent inwardly after the insertion of the ball or head, to retain the latter in place, whereby a mode of connection is provided which simplifies the construction of the die and reduces the number of employed parts. A coiled backing spring 13 incloses the shank and convex surface of the lug and bears against the back of the 60 die body so as to normally hold it in working position, while telescopically coupling the handle and die to permit relative universal motion between the same, whereby the die is adapted to be firmly impressed 65 regardless of the angle at which the handle is held on each stamping action. A sleeve or ferrule 14 is fitted upon the handle and projects beyond the same to inclose the upper end of the spring, whereby lateral undue 70 distention of the spring is prevented and the spring maintained in proper position to compensate for the angular disposition of 75 the handle and shank.

It will be understood from the foregoing 80 description that the described construction of the joint enables the die to be conveniently connected with the head of the shank and the device as a whole to be economically manufactured. Such construction also reduces the number of parts and the liability 85 of the tool getting out of order. By arranging the handle and shank at an angle provision is made to adapt the device to be held and used more comfortably and conveniently by the operator and with less strain upon the hand and wrist in stamping 90 a large amount of mail matter, as will be readily understood.

Having thus described the invention, what 95 I claim as new is:

A stamp canceling device comprising a die having a dome-shaped boss or projection of less diameter than said die and provided with a socket, a stem having a symmetrical 100 head fitting within the socket, whereby the die and stem are universally jointed, a handle receiving the opposite end of the stem, said stem and handle having their longitudinal axes arranged substantially at an 105 obtuse angle to each other, a sleeve inclosing the lower end of the handle and upper end of the stem and spaced from the die and

leaving the lower end of the stem exposed, and a coiled spring bearing respectively at its opposite ends against the die about the dome-shaped boss and against the lower end of the handle, said spring being arranged to inclose the stem and having its upper end inclosed within the sleeve.

In testimony whereof I affix my signature in presence of two witnesses.

WILLIAM MOLT.
